CLAIM

The ornamental design for a surgical instrument shaft, as shown and described.

DESCRIPTION

FIG. 1 is a perspective view of a surgical instrument shaft. FIG. 2 is a top plan view of the surgical instrument shaft of FIG. 1.

FIG. 3 is a bottom plan view of the surgical instrument shaft of FIG. 1.

FIG. 4 is a left elevation view of the surgical instrument shaft of FIG. 1.

FIG. 5 is a right elevation view of the surgical instrument shaft of FIG. 1.

FIG. 6 is a front elevation view of the surgical instrument shaft of FIG. 1; and,

FIG. 7 is a rear elevation view of the surgical instrument shaft of FIG. 1.

In all figures, broken lines illustrate environmental structures and form no part of the claimed design.
